Fig. 2,

Inventor,
John P. Ball.

UNITED STATES PATENT OFFICE

JOHN P. BALL, OF CHICAGO, ILLINOIS

BREAKWATER WALL CONSTRUCTION

Application filed April 23, 1931. Serial No. 532,200.

My invention relates to marine walls, for shore protection, of construction and design or shape approaching the cycloidal curve defined by the on-coming water wave and therefore a wall adapted, as it were, to trip the wave and permit it to ride upward upon the wall instead of impacting itself against the wall and thus subjecting the wall to its destructive force and strain.

10 The force of impact of a wave (whether it be a tidal or a wind wave) depends on the nature and shape of the wall which the wave strikes; and as waves, in transverse section, assume cycloid curves, I have devised a wall 15 of such arcuate formation approximating the cycloidal movement of the waves that the latter are permitted to ride upward onto the wall and their destructive action or force dissipated by reason of the engagement with 20 the lower side of the orbit or plane of movement of the on-coming wave.

Another object of my invention is to provide a wall which may be easily constructed without need for the construction of an extensive and therefore expensive base or foundation beneath the mean water level as has heretofore generally been the case.

The objects and advantages of my invention will be readily comprehended from the 30 following detailed description of the accompanying drawings, wherein:

Figure 1 is a top plan view of a portion of my improved wall, broken away in an irregular manner to more clearly show the construction.

Figure 2 is a transverse sectional view of the wall taken substantially on the line 2—2 of Figure 1.

In constructing my improved wall, the 40 course of the wall is first outlined by means of suitable piling or guide posts, indicated at 10, which are driven into place at predetermined distances apart and allowed to extend sufficiently above the water level to permit 45 proper aligning of the wall.

Pipes 11, 11 are then laid on the bottom on opposite sides of the guide-posts and disposed in the direction of the wall as shown.

These pipes, of predetermined length and 50 diameter and of sufficient thickness to with-

stand the weight and strains, are preferably of the welded spiral steel or corrugated construction as shown and are arranged with their ends in juxtaposition, namely end to end, throughout the length of the wall. Before placing the course or line of tubing or pipe in place, the pipe sections to be disposed on opposite sides of the row of guide-posts are suitably tied together, as for example by means of the metal bands 12, which, in turn, 60 are secured to the ends of the tie rods or steel cables 13, in order that the two lines of pipes may be held in proper position relative to each other and to the row of guide-posts to which the tie-rods 13 are suitably secured. 65 The tie-rods or cables 13 are made to encircle the guide-posts 10, as shown at 14, so as to hold the pipes 11 in proper position. I prefer to employ a tie-rod or cable 13 for each guide-post in order that the pipes 11 may be 70 securely held throughout their lengths.

The lower course of pipes 11 are laterally spaced apart in keeping with the intended width of the base of the wall and therefore the tie-rods 13 are of length commensurate 75 with the intended transverse dimensions of the wall base.

The pipe sections, at the initial end of the wall and before being laid, are provided with suitable headers or stops at the initial ends 80 and after being put into position are then filled with concrete, as shown at 15, by any suitable means whereby the concrete will flow into the open ends of the pipe-sections.

The pipe-sections or their headers are provided with temporary vents or openings for escape of the air and water as the concrete is being introduced and thus enable the pipe to be completely filled with concrete. These 85 vents may then be removed or closed.

The various pipe-sections are preferably filled one at a time and in order that the respective pipe-sections may be tied together, each succeeding section is filled with concrete to a point slightly removed from the 95 end adjacent to the next succeeding pipe-section so as to permit the concrete to fill said end while it is being introduced into the next succeeding pipe-section. It is apparent that the various sections of a course or line of 100

pipe will thus ultimately be completely filled with a continuous lot of concrete.

5 After the first or bottom course of pipe has been put into place at the bottom of the water, the space between the parallelly arranged, spaced apart pipe 11, is then filled with rubble or quarry-run stone, as shown at 16. The second course of pipe 17, of construction similar to the pipe 11, is then arranged on top of the first course or line of pipe; the pipe-sections 17 being also held in position by the tie-rods or cables 13 as previously described.

15 As my improved wall is intended to be of the arcuate formation shown, the tie-rods or cables 13 of the second course or line of pipe are of shorter length than the tie-rods or cables of the first course, so as to position the 20 pipe-sections 17 on opposite sides of the guide-posts 10 somewhat closer together as shown.

25 This second course is then filled with concrete in the manner previously described; the second course or line of pipe 17 resting partially on the first course or line of pipe 11 and on the filling of rubble 16. The space between the pipe sections 17 on opposite sides of the guide-posts 10 is then also filled in with the rubble or quarry-run stone 16, up to the 30 tops of the pipe-sections 17.

35 The third course or line of pipe 18 is then put into place on opposite sides of the guide-posts 10 after having provided the pipe sections with tie-rods or cables 13 of length somewhat shorter than those of the pipe lines 17, so as to position the pipe-sections 18 on opposite sides of the guide-posts 10 somewhat closer together as shown. These pipe-sections 18 are then filled with the concrete 40 15 as previously described and the space between the pipes on opposite sides of the posts 10 then filled in with the rubble or quarry-run stone 16; after which the next succeeding course of pipe 19 is put into place and held in position by tie-rods or cables 13 somewhat shorter than the cables of the preceding 45 lines of pipe 18. The space between the last mentioned lines of pipe 19 is then likewise filled in with the rubble or quarry-run stone 50 as shown.

55 A sufficient number of courses or lines of pipe are employed so as to have the topmost course or line of pipe preferably disposed above the normal water-level.

60 The rubble or quarry-run stone is mounded up into the arcuate manner shown and the top of the rubble then preferably provided with a plain concrete cap or covering 20, in keeping with the rounded mound of rubble, extending from the pipe sections 19 on one side of the guide-posts 10 to the pipe sections 19 on the opposite side so as to completely cover the rubble mound.

65 By forming the sides of the wall of continuously lengths of pipe of large diameter,

the mound of rubble is held in position against the action of the water; and with the courses of pipe tied to the snubbing or guide-posts and the rubble arranged about the posts, the composite wall is firmly anchored in place.

70 My improved wall, aside from its service-ability and the principle involved, can be more easily constructed than breakwater walls as heretofore constructed, as it eliminates the construction of a costly coffer-dam for proving a concrete covering on the sides of the rubble mound; and also eliminates the use of expensive pre-cast hollow caissons subsequently floated into position and then filled 80 with stone or concrete.

75 My improved arcuate wall of a curvature having a diameter preferably greater than the depth of the water in which the wall is built, approximates the cycloidal wave formation; and contact with the lower or under side of the waves is made, providing a tripping effect on the waves which results in a dissipation of their force and allows the less forceful broken or interrupted waves to ride 90 upward on the wall instead of pounding against and breaking over and on top of the wall.

85 What I claim is:

1. A breakwater wall construction adapted 95 to be built on the bed of a body of water and consisting of elongated members arranged in superposed rows on opposite sides of the wall with the successive rows from bottom to top on opposite sides being arranged at a gradually diminishing distance apart, means whereby the members on opposite sides are held against separating movement; a filling material between the rows of members on opposite sides of the wall, said filling material 100 extending into a plane above that of the top-most rows of members and arranged in an arcuate mound; and a covering for said mound of filling extending from side to side between the top rows of members.

105 2. A breakwater wall construction adapted to be built on the bed of a body of water, comprising continuous lines of pipe arranged in superposed rows on opposite sides of the wall with each successive row on each side from bottom to top being arranged a lesser lateral distance apart, said pipes being filled with concrete whereby aligned pipes are joined together; a filling of loose stone between the spaced apart lines of pipe, said filling being 115 mounded into an arcuate formation above the topmost rows of pipe; and a covering of concrete for said arcuate mound of filling extending from side to side between the topmost rows of pipe.

120 3. A breakwater wall construction adapted to be built on the bed of a body of water, comprising continuous lines of pipe arranged in superposed relation on opposite sides of the wall with each successive line from bot-

tom to top arranged closer to the median line of the wall, the respective lines of pipe being filled with concrete so as to tie the pipes of each line together; tie means between the corresponding lines of pipe on opposite sides of the wall; a filling of stone between the spaced apart lines of pipe, said filling extending above the upper lines of pipe and mounded into arcuate formation; and a covering of concrete for the filling extending from side to side between the topmost lines of pipe, the wall in cross section defining a cycloid curve.

4. A breakwater wall construction adapted to be built on the bed of a body of water and comprising a plurality of cylindrical members arranged in superposed rows on opposite sides of the wall with the corresponding rows arranged at gradually lesser distances apart from the bottom toward the top of the wall to provide a plurality of convex surfaces receding from bottom to top toward the longitudinal center of the wall, means for maintaining the opposite rows against outward movement, a mound of filling material between the rows of members, and an arcuate covering for said mound extending from side to side between the topmost rows of members and bounded by said members.
